CHAIR BODY

Randall P. Buhk, Wyoming, Mich., assignor to Steelcase,
Inc., Grand Rapids, Mich.

Filed Apr. 20, 1970, Ser. No. 22,513

Term of patent 14 years

Int. Cl. D6—02

U.S. Cl. D15—1

FIG. 1.

FIG. 2.

FIG. 3.

FIG.4.

FIG.5.

FIG.6.

FIG. 7.

FIG. 8.

FIG. 1 is a front perspective view of the chair body;
 FIG. 2 is a side perspective view of the chair body;
 FIG. 3 is a rear perspective view of the chair body;
 FIG. 4 is a plan perspective view of the chair body;
 FIG. 5 is a perspective view of the chair body;
 FIG. 6 is a perspective view of the chair body;
 FIG. 7 is a perspective view of an alternative embodiment of the chair body in which alternative seat and back cushions have been substituted; and

FIG. 8 is a perspective view of the alternative embodiment for the chair body which is shown in FIG. 7.

The design is characterized by the combination on the chair body disclosed being comprised of the shell and cushion arrangement in association with the specifically configured arm rest members and their orientation with

respect to the chair body, all as best illustrated in FIGS. 2, 7 and 8.

I claim:

The ornamental design for a chair body, substantially as shown and described.
